UNITED STATES PATENT OFFICE

DENFORD A. BRUMBAUGH, OF EVANSTON, ILLINOIS, ASSIGNOR TO NORTH AMERICAN SERVICE COMPANY, OF CHICAGO, ILLINOIS, A CORPORATION OF ILLINOIS

SIGN

Application filed May 3, 1928. Serial No. 274,738.

My invention relates to signs and more particularly to highway signs.

An object of my invention is to provide a sign of this type which is neat in appearance, strong and durable, and capable of display on both sides.

Highway signs have as a general rule been bulky and unattractive. This is due largely to their construction which must be rigid and durable to overcome wind stresses and permit exposure to changing weather conditions throughout the year. Signs which are made bulky, are not attractive, and do not as a rule permit the use of both sides for display purposes.

My invention provides a construction which is extremely pleasing in appearance, tending to beautify the surrounding rather than to detract from it, and which is simple, durable and an efficient advertising medium along highways.

Other objects and advantages of my invention will be apparent from the following detailed description taken in connection with the accompanying drawings forming a part hereof.

In the drawings:

Figure 1 is a perspective view of a highway sign embodying my invention; Fig. 2 is a vertical sectional view of the sign shown in Fig. 1;

Fig. 3 is an enlarged vertical sectional view of the fastening means employed to secure the display board and scroll to the frame; and

Fig. 4 is a sectional view of the fastening means employed to secure the ends of the frame member to the outer sides of the supporting posts.

I do not intend to limit my sign for a use to highway advertising solely, inasmuch as it is possible to employ the same construction for signs adapted to other purposes.

The sign comprises supporting posts 1 and 2 preferably held in spaced relation by a reinforcing member 3, secured at or near the upper ends of the posts. In order to support a display board 4 above the structure just described, I provide a frame of substantially inverted U-shape having its free ends secured

to the outer opposite faces of posts 1 and 2. This frame is preferably made of tubular metal and bent into shape so as to cooperate with supporting posts 1 and 2 in providing an opening 5, in which display board 4 is accommodated. Frame 6 is preferably curved at its upper corners 7 to give a neater appearance and provide greater strength.

By using tubular metal, it is comparatively easy to obtain the shape illustrated in the drawings, while, on the other hand, it is found that tubular metal is substantially stronger than flat metal and provides a neater appearance. The ends of the tubular metal may be flattened, as indicated at 8 in Figures 1 and 4, so as to lie against the outer sides of posts 1 and 2. Any suitable fastening means may be used, such as, for instance, bolts 9. Bolts 9 may extend through the supporting posts 1 and 2 so as to connect these ends 8 of frame 6 thereto.

It will be observed that sign board 4 is arranged to be suspended within the plane of frame 6. Any suitable suspending means may be employed, but I have illustrated fastening means comprising a plurality of U-straps 10 adapted to embrace the upper edge of display board 4 and to be secured thereto by screws or bolts 11. Bolts 12 are adapted to pass through the upper edge of frame 6 so as to allow the lower ends to be bent into an elongated loop 13 for the reception of straps 10. Suitable locking nuts 13 and 14 may be furnished to hold bolts 12 in position.

A further advantage of frame 6 resides in the fact that any suitable design or scroll work may be connected to the upper part of the sign so as to balance the design as a whole and render it exceptionally pleasing in appearance. It will be observed that bolts 12 pass through portions of the scroll 15 at the points 16 and 17 for securing the same to the frame. Obviously bolts 12 advantageously serve as a common means for securing the display board 4 and the scroll 15 to frame 6.

From the above description, it is apparent that the sign I have provided is extremely simple, inexpensive to manufacture, and involves practically little expense to maintain. It will also be apparent, by referring to Fig-

ures 1 and 2, that both sides 15 and 16 of the sign may be advantageously used for display purposes. The sign may be placed adjacent to the road in a position to permit travelers coming in opposite directions to view the opposite sides 15 and 16.

The form of structure which I have disclosed very aptly resists the wind stresses. It is ruggedly constructed and without being cumbersome and is capable of withstanding the changing weather conditions from time to time. It is not essential that reinforcing member 3 be furnished at the upper ends of posts 1 and 2. I find, however, that this reinforcing member serves to brace the posts and provide a general rectangular effect to aptly accommodate the display board 4 within a somewhat rectangular appearing opening 5.

I do not intend to limit my invention to any of the details of construction inasmuch as it is possible for one skilled in the art to make modifications of the structure herein shown without departing from the spirit of the invention, as defined in the appending claims.

I claim:

1. A sign comprising a pair of spaced supporting posts mounted in the ground at one end and held apart at the opposite end in rigid supporting relation by a cross member, an inverted U-shaped frame member carried by said posts, a panel in said frame member, said frame member having its ends shaped to conform to the sides of said posts, and removable fastening elements securing said frame member at its ends to the outer sides of said posts whereby said frame member and said panel may be removed without removing said posts and said cross member, the ends of said posts being shaped to conform to the contour or outline of said frame member and said cross member about said panel.

2. A sign comprising a pair of rigidly mounted supporting posts of substantial cross section, a cross member at the upper end of said posts for holding said posts in spaced relation, an inverted U-shaped hollow frame member of relatively smaller cross section carried by said posts, a panel carried by said frame member, said frame member having its ends flattened to conform to the sides of said posts, and removable fastening elements securing said frame member at its ends to the outer sides of said posts whereby said frame member and said panel may be removed without removing said posts and said cross member, the ends of said posts being cut to conform to the outline of said frame member and said cross member about said panel.

In witness whereof, I have hereunto subscribed my name.

DENFORD A. BRUMBAUGH.
